FIG. 2.

INVENTOR.
Astor Oelschleger
By his Atty.
Henry Wurtham

UNITED STATES PATENT OFFICE.

ANTON OELSCHLEGER, OF BOSTON, MASSACHUSETTS.

BRUSH FOR CLEANING CHIMNEYS.

SPECIFICATION forming part of Letters Patent No. 328,967, dated October 27, 1885.

Application filed May 23, 1885. Serial No. 166,915. (No model.)

To all whom it may concern:

Be it known that I, ANTON OELSCHLEGER, of Boston, in the county of Suffolk and State of Massachusetts, have invented a new and 5 Improved Brush for Cleaning Chimneys, of which the following is a specification.

In the accompanying drawings, in which similar letters of reference indicate like parts, Figure 1 is a plan view of my device, the 10 handle being shown in cross-section, and a portion of the body being represented as broken out, the better to illustrate the invention. Fig. 2 is a sectional view on line *x*, Fig. 1.

15 A represents a handle, of sufficient length to extend down a chimney, secured to a socket, B, set into the body in any suitable manner, the means shown being a nut, *a*. The body of the brush is of rectangular shape, so as to 20 fit into the corners of the chimney, and consists of radiating arms C and rims C' C'', supported by said arms, all made preferably in a single piece, and of rubber, leather, or other flexible material. The outer edges of the 25 rims are rounded and provided with bristles D, and the ends of said rims are preferably

made to overlap, as shown. The entire body, including the arms C and rim C' C'', is provided with internal metallic springs, E, as shown, set into the material, whereby greater 30 stiffness and firmness are obtained.

As the brush is worked back and forth in the chimney, the rectangular shape causes it to extend well into the corners, and the rigidity of the body adds greatly to its efficiency, 35 while the soot drops readily through the spaces between the radial arms.

Having thus fully described my invention, what I claim, and desire to secure by Letters Patent, is—

The herein-described improved brush for 40 cleaning chimneys, consisting, essentially, of the radial arms C and rims C' C'', made of rubber, leather, or other flexible material, provided with internal springs, E, and suitable 45 bristles and handle, substantially as and for the purpose described.

ANTON OELSCHLEGER.
